UNITED STATES PATENT OFFICE

1,984,638

BURIAL VAULT

Charles E. Glass, Fort Dodge, Iowa

Application February 19, 1934, Serial No. 711,956

1 Claim. (Cl. 27—35)

The object of my invention is to provide a burial vault which is simple, durable and comparatively inexpensive to manufacture.

More particularly, it is my object to provide a burial vault having what may be termed runners, shoes or skids designed to facilitate loading, unloading and handling of the burial vault and to also facilitate the operation of latches ordinarily provided for latching the vault cover to the vault base.

Still a further object is to provide runners so designed that they support the vault base against sagging and dropping down while the burial vault is in the ground as time passes, thus acting as a means to prevent distortion of the base and insure that it will retain its original shape.

With these and other objects in view my invention consists in the construction, arrangement and combination of the various parts of my device, whereby the objects contemplated are attained, as hereinafter more fully set forth, pointed out in my claims, and illustrated in the accompanying drawing, in which:

Figure 1 is a bottom perspective view of a burial vault embodying my invention.

Figure 2 is a longitudinal sectional view of the same on the line 2—2 of Figure 1.

Figure 3 is a lateral sectional view on the line 3—3 of Figure 1.

Figure 4 is a perspective view of one of the runners used on the burial vault; and

Figure 5 is a sectional view on the line 5—5 of Figure 3 illustrating one of the latches.

On the accompanying drawing, I have used the reference character B to indicate a vault base and C to indicate a front cover therefor. The base B has end edges 10 and side edges 12, the portion of the base intermediate these edges being upwardly recessed and indicated at 14.

The cover C is in most burial vaults latched in position by latches which operate automatically when the cover is placed on the base. On the drawing I have shown these latches at 16 and consisting of dogs pressed by springs 18 to engage in sockets 20 of the cover C. Guide pins 22 guide the dogs in their movement and the dogs have downwardly extending fingers 24 with which sliding wedges 26 may coact for retracting the dogs from the sockets 20. The wedges 26 are slidably mounted by means of a slot and pin connection indicated at 28—30 and have flanges 32 adapted to be engaged by an operator's fingers 34 for moving the wedges in a downward direction as shown by the arrow a

in Figure 5 when it is desired to release the dogs.

I provide a pair of runners A for the burial vault, each comprising a web 36 and a flange 38. The flange 38 is upcurved as at 40 and terminates in upwardly bent flanges 46.

The webs 36 are cut away as indicated at 42 so as to fit the edges 10 of the base B as best shown in Figure 2.

The runners A may be welded or otherwise 10 suitably secured to the base B with the flanges 46 embedded in recesses 48 in the edges 10 of the base.

The upcurved portions 40 enable the runners to climb up on small irregularities and obstructions 15 as the burial vault is slid across a surface, the flanges 46 protecting the edge 10 of the base B against deforming this edge when striking obstructions. The flange 38 of the runner A, it will be noted, is positioned well below the bottom 20 peripheral edge of the vault base B. This keeps the edge portions 10 and 12 of the base well above a platform or the like 50 when the vault structure is resting thereon. This enables the operator's 25 hand 34 to be conveniently inserted beneath the vault for operating the latches or dogs 16 as illustrated in Figures 3 and 5.

Due to the T-shape construction of the runners, they provide wide surfaces for resting on a depot platform, floor or other level surface, making it 30 much more convenient to handle a vault, especially when there are a casket and human body within it, the vaults themselves usually weighing approximately four-hundred and fifty pounds.

The vault can be readily pushed into a hearse 35 with no damage to the finish or floor because the runners rest upon the floor or upon the rollers provided in the hearse without any injury to these parts because of the distribution of the weight. Preferably the runners are of metal which can 40 take a smooth finish or polish so as to minimize the danger of scraping surfaces over which they slide.

The T-shape of the runners also provides substantial reinforcement for the bottom of the base 45 B after it is placed in the ground.

Some changes may be made in the construction and arrangement of the parts of my device without departing from the real spirit and purpose of 50 my invention, and it is my intention to cover by my claims, any modified forms of structure or use of mechanical equivalents, which may be reasonably included within their scope.

I claim as my invention:—

In a burial vault construction, a vault base, a vault cover therefor and a pair of runners on said vault base extending longitudinally throughout the length thereof and having upcurved ends and surface supporting portions intermediate said ends positioned at an elevation lower than the edges of said vault base to engage a grave floor or

other surface on which the vault rests, said runners also having supporting flanges throughout their length extending from said surface engaging portions upwardly to the bottom of said base and adapted, through thrust, to rigidly support said bottom relative to said surface engaging portions. 5
